UNITED STATES PATENT OFFICE.

JOHN C. SPROULL, OF LAWRENCE, KANSAS.

ACETYLENE-GAS GENERATOR.

1,194,251.

Specification of Letters Patent.

Patented Aug. 8, 1916.

Application filed July 30, 1915. Serial No. 42,785.

To all whom it may concern:

Be it known that I, JOHN C. SPROULL, a citizen of the United States, residing at Lawrence, in the county of Douglas and State of Kansas, have invented new and useful Improvements in Acetylene-Gas Generators, of which the following is a specification.

This invention relates to improvements in acetylene gas generators.

In carrying out the present invention, it is my purpose to provide an acetylene gas generator wherein an auxiliary carbid container will be mounted within the main carbid container and capable of operation to release the carbid therefrom when the main container has become exhausted, the carbid from the auxiliary container being discharged into the main container.

It is also my purpose to provide an acetylene gas generator wherein the gas bell will be so arranged to the generating tank and the flow of gas from the generating tank to the bell such that the leakage of gas into the carbid container is prevented, thereby eliminating slaking of the carbid in the container and avoiding clogging of the valve controlling the flow of carbid from the container to the generating tank.

Another object of my invention is to provide an acetylene gas generator wherein the gas will be filtered previous to leaving the generating tank and the moisture removed therefrom and discharged back into the generating tank, thereby preventing the wet gas from entering the burners or other gas consuming devices.

A further object of my invention is to provide a generator of the class described wherein the auxiliary carbid container may be manually operated from the exterior of the generator to discharge the contents thereof into the main carbid container and wherein the discharge of the carbid from the auxiliary container to the main container will be such as to prevent the loss of the carbid, incident to such carbid flowing through the open valve of the main container into the water in the generating tank.

With the above and other objects in view, the invention consists in the construction, combination and arrangement of parts hereinafter set forth in and falling within the scope of the claim.

In the accompanying drawings, Figure 1 is a horizontal sectional view through an

acetylene gas generator constructed in accordance with the present invention. Fig. 2 is an enlarged fragmentary vertical sectional view through the generator showing the auxiliary carbid container and controlling mechanism therefor.

Referring now to the drawings in detail, 1 designates a generating tank of any desired capacity and having the lower end closed and the upper end portion circumferentially reduced to form a neck 2. In the present instance, the upper end of the neck 2 is open and disposed within the tank 2 is a main carbid container 3 in the form of a hopper and the upper end of the side wall of the hopper-shaped carbid container 3 is flanged outwardly as at 4 and the marginal edge of the flange secured to the upper edge of the neck 2, thus closing the neck of the generating tank. The lower portion of the generating tank 1 is designed to contain a quantity of water 5, while the carbid container 3 is adapted to hold a quantity of carbid 6. The lower end of the hopper-shaped container 3 is equipped with a controlling valve 7 controlling the flow of carbid from the container 3 into the tank 1 and the disk of the valve 7 is equipped with a stem 8 projecting upwardly through the carbid container 3 and having the upper end thereof terminating above such container. Closing the upper end of the carbid container 3 is a cover 9 resting upon the flange 4 and formed centrally with an opening through which the upper end of the stem 8 passes, while formed on the cover 9 concentrically of the stem 8 and surrounding the latter is a sleeve 10 having the lower end formed with a protector or shield 11 conical in shape and spaced apart from the bottom of the hopper-shaped container 3. This shield 11 supports the weight of the carbid within the container 3 so as to prevent such carbid from exerting undue pressure on the valve 7. Surrounding the neck 2 of the generating chamber and spaced apart therefrom concentrically thereof is a circular shell 12 having the lower end suitably secured to the generating chamber at the juncture of the neck with the bottom portion of such chamber. Disposed within the space between the neck 2 and the shell 12 is a quantity of oil, kerosene, water or analogous sealing material 13.

14 designates a bell having the side wall thereof immersed in the liquid 13 and ca-

pable of vertical movement therein, and the top end wall overlying the upper ends of the neck 2 and the hopper-shaped container 3.

In accordance with my present invention, 5 the neck 2, adjacent to the upper end thereof, is formed with a circular row of openings 15 establishing communication between the tank 1 and the bell 14, while mounted within the tank 1 below the container 3 is an 10 appropriate form of gas filter 16.

Connected with the lower end of the filter 16 and extending out through the side wall of the tank 1 is a supply pipe 17 leading to the burners or other gas consuming devices, 15 while connected to the pipe 17 below the filter 16 and extending down into the volume of water 5 in the tank 1 is a drain pipe 18 through which the moisture extracted from the gas by the filter 16 is discharged back 20 into the water 5 in the tank.

Secured to the bottom end wall of the tank 1 and in open communication therewith is a drain pipe 19 equipped with a cut-off valve 20 and leading to a suitable sewer or other place of drainage. The drain pipe 25 19 is employed only where the drain water may be discharged by gravity into the sewer, while in localities where no draining facilities are present, a pump 21 is employed. This pump is located at the desired elevation and connected by means of a depending vertical pipe 22 with the drain pipe 19. When the valve 20 is opened and the pump 21 placed in operation, the refuse 30 35 is pumped, out of the bottom of the generating tank 1.

In practice, when the gas bell 14 is lowered, such bell engages the upper end of the stem 8 and opens the valve 7 and when the 40 valve 7 is opened, the carbid feeds from the carbid container 3 into the water 5 in the tank 1. As the carbid enters the water the gas is generated and such gas flows upwardly around the container 3, through the 45 openings 15 into the bell 14, thereby elevating the bell and in the upward movement of the bell the stem 8 is released and the valve 7 closed by the pressure of the gas on the under side of the valve, thereby cutting off 50 communication between the carbid container and the tank. When the burners are in service the gas flows from the tank 1 through the filter 16 and the pipe 17 and as the gas is consumed the bell lowers and 55 again opens the valve 7 so as to generate the gas in accordance with the consumption thereof. As the gas passes through the filter 16, the moisture is extracted therefrom and the condensation is restored to the water 60 65 70 75 80 85 90 95 100 105 110 115 120 125 130 135 140 145 150 155 160 tween said neck and shell, a gas bell surrounding said neck and having the lower end thereof immersed in the sealing liquid and adapted to be elevated by the gas flowing from the generating tank through the opening in the neck thereof into the bell, a valve controlling communication between said carbide container and generating tank, an auxiliary carbide container in said first 10 container formed with a hinged bottom, an arm arranged at the upper end of said first carbide container and projecting therethrough into said auxiliary container, a chain connecting the lower end of said arm 15 to said hinged bottom, a vertical rod extending downwardly into the lower portion of

said neck and then bent upon itself and projecting upwardly through the inclined portion of the neck that connects said neck with the bottom portion of the tank, a tube surrounding the upwardly projecting portion of said rod and having the lower end thereof immersed in the liquid in said tank, and a connection between said arm and the adjacent end of said rod. 20 25

In testimony whereof I affix my signature in presence of two witnesses.

JOHN C. SPROULL.
